UNITED STATES PATENT OFFICE.

ANDREW H. HAVIR, OF MINNEAPOLIS, MINNESOTA.

AUTOMATIC CATTLE GUARD.

1,412,240.

Specification of Letters Patent. Patented Apr. 11, 1922.

Application filed March 17, 1921. Serial No. 453,091.

To all whom it may concern:

Be it known that I, ANDREW H. HAVIR, a citizen of the United States, residing at Minneapolis, in the county of Hennepin and

5 State of Minnesota, have invented certain new and useful Improvements in Automatic Cattle Guards, of which the following is a specification.

My invention relates to automatic cattle 10 guards. An object is to provide a device of this character embodying a gate or barrier which automatically raises and prevents animals from wandering on railroad crossings out upon the tracks at the sides of the 15 crossing. Another object is to provide a lock or catch which normally holds the gate in depressed position and which is released when an animal starts to cross the space protected by the guard.

20 The full objects and advantages of my invention will appear in connection with the detailed description, and the novel features embodied in my inventive idea will be particularly pointed out in the claims.

25 Referring to the drawings which illustrate the application of my invention in one form,

Fig. 1 is a top plan view of my device. Fig. 2 is a view in longitudinal vertical 30 section on the line 2--2 of Fig. 1. Fig. 3 is a view in longitudinal vertical section on the line 3--3 of Fig. 1. Fig. 4 is a view in transverse vertical section on the line 4--4 of Fig. 2. Fig. 5 is a view similar 35 to Fig. 3 showing the device unlocked. Fig. 6 is a similar view showing the device operated. Fig. 7 is a view in transverse vertical section on the line 7--7 of Fig. 1.

In the accompanying drawings, the customary railroad tracks are indicated at R and the customary cross ties are indicated at T. My automatic guard is made in sections, there being one of these sections between the two rails of a track and one at 45 each side of the track while in cases where more than one track occurs the sections are merely increased in proportion to the number of tracks so as to be located relatively thereto in a similar manner. When 50 the device or any section thereof is not operated, none of the parts thereof extend upwardly above the rails. Secured on top of the ties are strips 10 terminating adjacent the rails and to the ends of these strips 55 are secured angle members 12 which in turn serve to secure longitudinal bars or supports

14 which are thus held in position parallel to the rails. A gate is provided which consists of a frame having side members 16 and 18, a rear member 20 and a front member 60 22, the space within these members containing a wire mesh construction 24 or other suitable structure which prevents passage of animals through the frame. When the gate is in its lowered position as shown in 65 Figs. 2 and 4, the side members 16 and 18 thereof rest upon horizontal flanges of the angle members 12 and if desired the upper surface of these flanges may be provided with rubber or other suitable resilient material 25 to break the force with which the gate is stopped when it lowers. The side members 16 and 18 are provided with trunnions 26 as best shown in Fig. 1 by means of which the gate is pivotally attached to the 70 longitudinal bars 14. The side members 16 and 18 project forwardly a short distance as best shown in Fig. 1 and pivoted to these projecting ends are bars 28 and 30, the forward ends of which are provided with 75 rollers 32 and 34 which rest upon one of the strips 10 or a suitable support which may be provided. The rear ends of the bars 28 and 30 are connected by a narrow board or strip 36 and hinged to this board by hinges 80 38 is a platform 40 normally held upwardly by springs 42. Secured to the side members 16 and 18 of the gate adjacent the trunnions 36 are brackets 44 to which the rear ends of rods 46 are pivotally attached. The 85 front portions of these rods extend through ears 48 and at their ends are provided with nuts 50 adapted for engagement by springs 52 encircling the rods. The platform 40 is provided with a slot 54 bridged by a strip 90 56 which passes through an inclined slot 58 formed in the upwardly extending front end of a bar 60. This bar is slidably supported on account of being provided with longitudinal slots 62 through which extend 95 bolts or pins carried by angle members 64 mounted on a strip 66 and on the strips 10 pivotally referred to. The rear end of the rod 60 is turned upwardly and provided with a forwardly extending locking flange 100 68 which is adapted to engage over the rear member 20 of the gate when the rod is in its forward position as shown in Fig. 2. Secured to the rods 46 toward their forward ends but at a short distance in the rear of 105 the ears 48 are angle members having horizontal flanges 70 adapted to engage over the

front end of the platform when the latter is depressed as shown in Fig. 5 and the rods are moved rearwardly as shown in Fig. 6. It will be obvious that any number of these 5 sections may be employed according to the number of tracks located at any particular crossing.

The operation and advantages of my invention will be obvious from the foregoing 10 description. When a cow or other animal attempts to pass from the crossing over the space protected by the guard and steps upon the front end of the movable platform 40 this end is depressed from the position 15 shown in Fig. 3 to that shown in Fig. 5. The downward movement of the bridging strip 56 in the inclined space 58 formed in the upturned front end of the bar 60 causes this bar to slide rearwardly and remove the 20 flange 68 from engagement with the rear gate member 20 so that the gate is no longer held in its downward position. As the animal steps farther upon the platform, the rear portion thereof is depressed in opposition 25 to the tension of the springs 42, thereby swinging the front end of the gate downwardly upon the trunnions 26 as shown in Fig. 6. This causes the main portion of the 30 gate to swing upwardly, the construction preferably being such that the gate swings an angle of about 70° and then stops in this position. At the same time, the movement 35 of the brackets 44 causes the rods 46 to be pulled rearward and move the flanges 70 over the front end of the platform, whereby this end of the platform will be held down, even though the weight of the animal should be disposed entirely upon the rear portion of 40 the platform. If the front end of the platform were allowed to rise at this time, the flange 68 would move forwardly into locking 45 position at a time when the gate is raised but by means of this construction such result is positively prevented. The rearward movement of the rods 46 causes the springs 52 to be compressed. The animal when thus 50 prevented from going further will naturally back off the platform and as it does so, the rear end of the platform will rise and the 55 gate will lower into its depressed position, the compression of the springs 52 serving to help initiate the downward movement of the gate. The flanges 70 do not pass over from the front end of the platform until the gate 60 is completely lowered, whereupon the bar again engages the gate member 20 to lock 55 the gate in its lowered position.

I claim:

60 1. An automatic cattle guard comprising supports positioned adjacent the rails of a railroad, a gate pivoted to said supports on a horizontal pivot and normally in lowered horizontal position, means for locking said 65 gate in lowered position, and means for caus-

ing said gate to be unlocked and swung upwardly when an animal starts to cross the space protected by the guard.

2. An automatic cattle guard comprising supports positioned adjacent the rails of a 70 railroad, a gate pivoted to said supports on a horizontal pivot and normally in lowered horizontal position, a depressible platform in advance of said gate, connections between said platform and said gate whereby the 75 latter is swung upwardly when an animal steps on said platform, means normally locking said gate in lowered position, and means for releasing said locking means when said platform is depressed. 80

3. An automatic cattle guard comprising supports positioned adjacent the rails of a railroad, a gate pivoted to said supports on a horizontal pivot and normally in lowered horizontal position, a depressible platform 85 in advance of said gate, connections between said platform and said gate whereby the latter is swung upwardly when an animal steps on said platform, a slideable bar, means which slide said bar rearwardly when said platform is depressed, and means on said bar normally holding said gate down and released when said bar is slid rearwardly. 90

4. An automatic cattle guard comprising supports positioned adjacent the rails of a railroad, a gate pivoted near its forward end to said supports on a horizontal pivot and normally in lowered horizontal position, a strip pivotally attached to the forward end of said gate, a platform hinged to said strip, 100 springs normally holding said platform lifted, a strip which bridges a slot in the front portion of said platform, a slideable bar having an extension at its forward end containing an inclined slot through which said bridging strip extends, and a locking flange on the rear of said bar adapted to engage the rear member of said gate. 105

5. An automatic cattle guard comprising supports positioned adjacent the rails of a railroad, a gate pivoted near its forward end to said supports on a horizontal pivot and normally in lowered horizontal position, a strip pivotally attached to the forward end of said gate, a platform hinged to said strip, 110 brackets depending from the side members of said gate adjacent its pivotal attachment, rods pivoted to said brackets, ears secured to said supports and through which said rods extend, springs encircling said rods between 115 said ears and enlargements on the front ends of said rods, flanges secured to said rods for engaging the front end of said platform when the latter is depressed and the rods moved rearwardly, springs normally holding 120 said platform lifted, a strip which bridges a slot in the front portion of said platform, a slideable bar having an extension at its forward end containing an inclined slot through which bridging strip extends, 125 130

and a locking flange on the rear end of said bar adapted to engage the rear member of said gate.

6. An automatic cattle guard comprising
5 supports positioned adjacent the rails of a railroad, a gate pivoted near its forward end to said supports on a horizontal pivot and normally in lowered horizontal position, bars pivoted to the side members of said gate in
10 front of its pivotal attachment to said supports, rollers on the front ends of said bars, said rollers being supported near the top of the ties, a strip connecting said bars near their pivoted ends, a platform hinged to said
15 strip, brackets depending from the side members of said gate adjacent its pivotal attachment, rods pivoted to said brackets, ears secured to said supports and through

which said rods extend, springs encircling said rods between said ears and enlargements on the front ends of said rods, means 20 carried by said rods for engaging the front end of said platform when the latter is depressed and the rods moved rearwardly, springs normally holding said platform 25 lifted, a strip which bridges a slot in the front portion of said platform, a slideable bar having an extension at its forward end containing an inclined slot through which said bridging strip extends, and locking 30 means on the rear end of said bar adapted to hold said gate depressed and released when said bar moves rearwardly.

In testimony whereof I hereunto affix my signature.

ANDREW H. HAVIR.
